HANGING RECEPTACLE FOR BATH ARTICLES

Josef J. Bernay, 1138 S. Point View, Los Angeles, Calif.

Filed May 10, 1961, Ser. No. 65,106

Term of patent 14 years

(Cl. D4—3)

FIG. 1.

FIG. 2.

FIG. 3.

FIG. 4.

FIG. 1 is a perspective view of a hanging receptacle for bath articles showing my new design.

FIG. 2 is a side elevational view thereof.

FIG. 3 is a top elevational view thereof.

FIG. 4 is a perspective view taken from the rear and side thereof.

I claim:

The ornamental design for a hanging receptacle for bath articles, substantially as shown.
